(57) **CLAIM**

The ornamental design for a car phone holder, as shown and described.

DESCRIPTION

FIG. 1 is a front, right and perspective view of a car phone holder, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a decoration part.

FIG. 10 is a partial enlarged view of an area labeled 10 in FIG. 1 comprising grooves; and,

FIG. 11 is a cross-sectional view of the car phone holder of FIG. 1, taken along section line 11-11 as depicted in FIG. 7. The dash-dash broken lines shown in the drawings are included for the purpose of illustrating portions of the car phone holder that form no part of the claimed design. In addition, the dot-dash broken lines in the drawings illustrate the boundaries of the enlarged portions of the design.
